UNITED STATES PATENT OFFICE.

ALONZO ZIMMERMAN, OF ANSTED, WEST VIRGINIA.

METAL TIE AND RAIL-FASTENER.

1,078,326.

Specification of Letters Patent.

Patented Nov. 11, 1913.

Application filed August 5, 1912. Serial No. 783,133.

To all whom it may concern:

Be it known that I, ALONZO ZIMMERMAN, a citizen of the United States, residing at Ansted, in the county of Fayette and State 5 of West Virginia, have invented a new and useful Metal Tie and Rail-Fastener, of which the following is a specification.

The present invention relates to improvements in metal ties and rail fasteners, one 10 object of the present invention, being the provision of a tie provided with means for receiving the inner edge of the base flange of each rail and with manually controlled means for engaging the outer edges of such 15 flanges to lock the flanges upon the tie, there being provided where the tie is used in connection with a rail joint, means for properly connecting the joints together and at the same time holding an electrical bond in position where the rails are used as the return 20 for the traffic current, rendering the present device especially desirable in connection with mine railways.

A further object of the present invention 25 is the provision of a metallic rail tie and fastener, by means of which the rails are properly placed and held in position without the employment of spikes or bolts; thus in reality producing a temporary tie which may be 30 used as a permanent tie.

With the foregoing and other objects in view which will appear as the description 35 proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a top plan view of the tie in the position it assumes when in use. Fig. 2 is a side elevation thereof of dotted lines illustrating the position of the movable members, and the controlling lever when the rails are being positioned in place or being removed. Fig. 3 is a longitudinal sectional view through the tie and fastener with the lever in releasing position. 45 Fig. 4 is a top plan view of one end of the tie used in connection with a rail joint, the web of the rails at the joint being shown in section. Fig. 5 is a section taken on line 5—5 of Fig. 4. Fig. 6 is a view in elevation taken from the exterior side of the device as

shown in Fig. 5. Fig. 7 is a plan view illustrating the present invention in practice.

Referring to the drawings, the numeral 1 designates the two parallel plates which are held together by means of the two end bolts 2 and the central pivoting bolt 3, the two bolts 2 having disposed thereupon a spacing sleeve 4, which as will presently appear, also provides a means for properly guiding the movable rail clamping members of the tie. 65

Formed at each end of the two plates 1 upon the upper edge thereof are the upstanding cleats or lugs 5 which are shaped to receive one edge of the base 11 of the rail 10 while formed in the upper edge at a point 70 slightly within the lugs 5 is a recess 6 for the reception of one base flange 7 of the rail web engaging and bracing rail section 8. By this means a section of the rail, whether a discarded rail or not, may be employed in 75 connection with the present invention to be attached to this form of tie and engage the inner web of the rail as herein illustrated to brace the rail wherever necessary.

The hooked terminals 12 of the two rods 80 13 are disposed to be moved to and from the outer edges of the bases 11 of the two rails 10, their inner ends being pivotally connected at 14 and 14' above and below the pivoting or fulcrumming bolts 3 to the operating 85 lever 15. This lever when in the position as shown in dotted lines Fig. 2 and full line in Fig. 3, causes the relative movement of the hooked terminals 12 away from the base of the rail 10, but when used between the two 90 plates 1 being moved toward the left as viewed in Fig. 3, draws both of the hooked terminals 12 toward and into engagement with the outer edges of the base flanges of the two rails 10, forcing the inner edges of 95 the flanges into engagement with the lugs 5 and against the head of the bracing rail sections 8. By this means it will be seen that the rail is braced below the head at the web portion 9 and is held properly anchored to 100 the plates 1 which constitute the tying means between the rails.

It will thus be seen that with this structure, that the rails can be quickly positioned in place and that due to the clamping between the lugs 5 and the hooked terminals 11 of the clamping rods 13, the necessary longitudinal expansion due to temperature, is permitted in the rails.

The present tie is designed to be used as 110

2
a permanent or a temporary tie, and more particularly in connection with mining rail-ways where the rails are continually ex-
tended and removed due to the finishing of
old workings of the mine and the opening
of new workings.

In order to provide a means for properly connecting the joints of the rails 10^a and 10^b, as illustrated in Figs. 4, 5 and 6, there
10 is provided at one end of the two plates 1^a, which are constructed somewhat similar to the plates 1, the diverging lugs or arms 16, which are provided with the rounded ter-
minals 17 for passage through the apertures 15 of the copper bonding plate 18 and into the apertures 19 of the rail sections. By this means it will be seen that the rail joints may be properly positioned upon the re-
ceiving portions of the plates 1^a with their
20 flanges disposed adjacent the lugs 5, the cylindrical terminals 17 being disposed through the apertures of the bonding plate 18 and the apertures 19 of the rail sections 10^a, thus providing a means when the
25 hooked portion 12' through its operating rod 13' is moved into engagement with the base 11^a, as shown in Figs. 5 and 6, will properly hold the rail seated upon the tie and at the same time will bind the copper
30 bonding plate 18 in proper position so as to render the rail electrically continuous. By this means, the bonding plate is applied and held in position by the same means that locks the joints together.

35 When the present device is used in connection with mines, the sections of the rails being usually 30 feet long, it is not always practicable to mount the ends of the rails 10 at the desired distance from the head of the workings, therefore, the two rail sections 8, as shown in Fig. 7, are clamped so that the sides of the heads thereof beyond the ends of the rails 10, will be projected to receive the wheels of the car, it being
40 easy to release the rail sections 8 and extend them successively as the coal is cut from the head of the workings. When the sections 8 have been extended their full dis-
tance, two new sections 10 are then placed
45 at the ends of the last sections 10 and the extension rails 8 mounted as before, so that such extension rails are in a position to be readily put in use as the occasion requires.

50 What is claimed is:
55 1. A rail tie and fastener, including two longitudinal plates, the rail bearing por-

tions of which are provided with means to receive the inner edges of the bases of two rails, two slideable rods each having a hooked terminal to embrace the outer edge of a rail base, and a lever pivoted between the plates and connected to the inner ends of the rods for operating the rods.

2. A rail tie and fastener, including two longitudinal plates, the rail bearing por-
tions of which are provided with means to receive the inner edges of the bases of two rails, two slideable rods, each having a hooked terminal to embrace the outer edge of a rail base, a lever pivoted between the plates and connected to the inner ends of the rods for operating the rods, and means for holding the outer ends of the longitudinal plates spaced, said means also consti-
tuting a guiding means for the free ends of the rods. 75

3. A rail tie and fastener, including two longitudinal plates, the rail bearing por-
tions of which are provided with means to receive the inner edges of the bases of two rails, two slideable rods each having a hooked terminal to embrace the outer edge of a rail base, a lever pivoted between the plates and connected to the inner ends of the rods for operating the rods, and two extension rail receiving means disposed one to each red to coat with the main rails and the hooked terminals to be held to the tie. 80

4. A rail tie and fastener, including two longitudinal plates, the rail bearing portions of which are provided with means to receive the inner edges of the bases of two rails, two slideable rods, each having a hooked terminal to embrace the outer edge of a rail base, a lever pivoted between the plates and connected to the inner ends of the rods for operating the rods, means for holding the outer ends of the longitudinal plates spaced, said means also constituting a guiding means for the free ends of the rods, and two extension rail receiving means disposed one to each rod to coat with the main rails and the hooked terminals to be held to the tie. 90

In testimony that I claim the foregoing as my own, I have hereto affixed my signature 95 in the presence of two witnesses.

ALONZO ZIMMERMAN.
